US00D639632S

(12) **United States Design Patent**
Freeman et al.

(10) **Patent No.:** US D639,632 S
(45) **Date of Patent:** ** Jun. 14, 2011

(54) **KNIFE HANDLE**

(75) Inventors: **Jeffrey Freeman**, Tigard, OR (US);
Darrin Seeds, Vancouver, WA (US)

(73) Assignee: **Fiskars Brands, Inc.**, Madison, WI (US)

(**) Term: **14 Years**

(21) Appl. No.: **29/316,494**

(22) Filed: **Oct. 2, 2009**

(51) **LOC (9) Cl.** 08-03

(52) **U.S. Cl.** D8/99

(58) **Field of Classification Search** D7/649;
D8/95-99, 107; D22/118; 30/154-162,
30/329-331

See application file for complete search history.

(57) **CLAIM**

We claim the ornamental design for a knife handle, as shown and described.

DESCRIPTION

FIG. 1 is a perspective view of the knife handle.

FIG. 2 is a front view of the knife handle.

FIG. 3 is a rear view of the knife handle.

FIG. 4 is a left side view of the knife handle.

FIG. 5 is a top view of the knife handle.

FIG. 6 is a right side view of the knife handle; and,

FIG. 7 is a bottom view of the knife handle.

The broken lines shown in the drawings illustrate environmental structure and form no part of the claimed design.
